CURTAIN STRETCHER

William Bheight, Youngstown, Ohio

Application March 18, 1937, Serial No. 131,572

1 Claim. (Cl. 45—24)

This invention relates to curtain stretchers. The principal object of this invention is to provide a curtain stretcher which is adjustable to accommodate curtains of different sizes.

5 A further object of this invention is to provide a curtain stretcher on which curtains may be quickly and easily placed and removed.

Another object of this invention is to provide 10 a curtain stretcher having a plurality of hooked rods as the principal means of holding the curtains being stretched.

A still further object of this invention is to 15 provide a curtain stretcher which is of simple, strong, and durable construction, and which is cheap and easy to produce and is thoroughly reliable and efficient in use.

With the foregoing and other objects in view which will appear as the description proceeds, 20 the invention resides in the combination and arrangement of parts and in the details of construction hereinafter described and claimed, it being understood that changes in the precise embodiment of the invention herein disclosed, can be made within the scope of what is claimed, 25 without departing from the spirit of the invention.

The invention is illustrated in the accompanying drawing, wherein—

Figure 1 is a plan view of a curtain stretcher 30 with parts broken away, and showing fragments of a curtain stretched thereon.

Figure 2 is a plan view of a modification of one 35 end of the curtain stretcher shown in Figure 1.

Figure 3 is a detail view of one of the rods and 40 the means for holding it in position.

By referring to the drawing it will be seen that 45 there is provided a curtain stretcher comprising a pair of upright frame members 1 and 2. These frame members have legs hinged to the back thereof in order to hold the entire device in an upright position. A pair of rails 3 and 4 are positioned across and bolted to the upright frame members. These rails 3 and 4 are provided with a plurality of studs 5 adapted to hold metallic hooked rods 6 and 7 in proper position. A pair 50 of braces 11 are provided to hold the assembled curtain stretcher in an upright position. These braces are pivoted to the rail 3 and catches are provided on the upright frame members 1 and 2 to receive the opposite ends of the braces. These

braces may be formed of either wood or metal as desired. Vertical slots are provided in the lower portions of the upright frame members to allow the lower rail 4 to be adjusted vertically.

By referring to Figure 3 it will be seen that one 5 of the metallic hooked rods is shown positioned over the rail 3 and held in place by one of the studs 5. The rails 3, and 4 are provided with a plurality of pins 10, adapted to hold the edges of the curtain when their use is necessary. In 10 normal operation, the curtain is held entirely by the rods 6 and 7 which are threaded through the hems of the curtains and hooked over the top rail 3 and held in position by means of the studs 5. These studs 5 are arranged so that any length of 15 curtain may be efficiently stretched, as they provide various locations for placing the rods.

By referring to Figure 2 it will be seen that a 20 modification is provided at the right side of the device shown in Figure 1 in that a rail 8 is shown positioned over two of the studs 5 and held in that position through the clamping action of a hooked metallic rod 9. This modification is provided for 25 use in the event that one or both hems of the curtain will not permit the insertion of the metallic rod, or at such times as a lace tablecloth or other similar article is being stretched. It is 30 obvious that this modification can be adapted for use at the left side of the curtain stretcher as well as at the right as shown.

What I claim is:

In a curtain stretcher comprising a pair of 35 upright frame members, each having a slot at its lower end, a horizontal upper rail bolted to said vertical frame members and a lower horizontal rail 40 adjustably positioned on the lower portion of said upright members by means of bolts functioning in said slots, a pair of braces between the upper rail and the upright frame members, in combination with a plurality of pins and a 45 plurality of studs positioned on said rails, metallic hooked bars adapted to be hooked over the upper one of the said rails and held in position by said studs, a secondary slotted rail provided with a plurality of pins and adapted to be positioned over two of said studs and held in that 50 position through the clamping action of one of said hooked metallic rods.

WILLIAM BEIGHT. 50
